Primary Examiner — Rebekah A Caruso(74) *Attorney, Agent, or Firm* — LIN & ASSOCIATES INTELLECTUAL PROPERTY, INC.(57) **CLAIM**

The ornamental design for a mobile phone clamp, as shown and described.

DESCRIPTION

FIG. 1 is a perspective view of a mobile phone clamp showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof;

FIG. 8 is a perspective view of the mobile phone clamp viewed from another direction;

FIG. 9 is a perspective view of the mobile phone clamp showing a first use state; and,

FIG. 10 is a perspective view of the mobile phone clamp showing a second use state.

The portions of mobile phone clamp shown in broken lines form no part of the claimed design, and the broken lines showing a cylindrical element in FIGS. 9 and 10 depict environmental structure that forms no part of the claimed design.

1 Claim, 7 Drawing Sheets(56)
